DESIGN FOR A BOTTLE

Frank Earl Higgins, New York, N. Y., assignor to California Perfume Company, Inc., New York,
N. Y., a corporation of New York

Application November 23, 1936, Serial No. 66,093

Term of patent 14 years

To all whom it may concern:

Be it known that I, Frank Earl Higgins, a citizen of the United States, residing at New York, county and State of New York, have invented a new, original, and ornamental Design for a Bottle, of which the following is a specification, reference being had to the accompanying drawing, forming a part thereof.

In the drawing:—

Fig. 1 is a front view of a bottle showing my new design.

Fig. 2 is a side view thereof.

Fig. 3 is a top view thereof.

Fig. 4 is a perspective view with the bottom of the bottle broken away.

I claim:—

The ornamental design for a bottle as shown.

FRANK EARL HIGGINS.
